UNITED STATES PATENT OFFICE.

HAROLD B. CRAIG, OF SPRINGFIELD, MASSACHUSETTS.

TEASPOON AND TABLESPOON LEVELER.

1,383,603.

Specification of Letters Patent.

Patented July 5, 1921.

Application filed November 16, 1920. Serial No. 424,355.

To all whom it may concern:

Be it known that I, HAROLD B. CRAIG, a citizen of the United States of America, residing at Springfield, in the county of 5 Hampden and State of Massachusetts, have invented certain new and useful Improvements in Teaspoon and Tablespoon Levelers, of which the following is a specification.

My present invention relates particularly 10 to devices for insuring the withdrawal of a leveled teaspoonful or tablespoonful of material from a container and finds its most important use in connection with the preparation of medicine doses and of food, particularly infants' food, my object being the 15 provision of a simple inexpensive device readily attachable to a bottle, jar, can or the like by means of which material withdrawn in the spoon is leveled off evenly with 20 the edge of the utensil in a ready, quick and convenient manner.

In the accompanying drawing which illustrates my present invention and forms a part of this specification,

25 Fig. 1 is a perspective view illustrating the practical application of my invention to a cylindrical vessel,

Fig. 2 is a vertical cross section there- 30 through,

Fig. 3 is a top plan view showing the rectangular form for application to cans,

Fig. 4 is a cross section through a form 35 of the invention as applied to screw top jars and the like, and

Fig. 5 is a cross section showing a modified form wherein the lip or leveling extension is braced or reinforced.

Fig. 6 is an inverted plan view of the 40 device as illustrated in Figs. 1 and 2.

Fig. 7 is a fragmentary inverted plan view 45 of the form of the invention shown in Fig. 4.

Fig. 8 is an inverted plan view of a frag- 50 ment of the modification shown in Fig. 5.

Referring now to these figures, it will be 55 noted that in each figure I have shown my improved device embodying a supporting band for engagement with the top of a receptacle, the plain circular band of Figs. 1 and 2 being applied to large mouth bottles and cylindrical containers of various natures whose upper open end the band 10 is adapted to encircle and embrace.

In Fig. 3 the band 10^a is shown rectangular for application to rectangular cans and 55 the like, while in Fig. 4 the circular band

10^b is shown threaded for application to screw top jars and the like.

In every instance the upper edge of the supporting band carries a disk or plate whose body is secured to the band or formed 60 integral therewith for a portion of its peripheral edge, which disk or plate has a free portion bent downwardly and inwardly with respect thereto to form a reverting flange and a leveling lip against which a 65 spoonful of material may be pressed in the course of its withdrawal from the container and readily and easily leveled with the edge of the spoon as may be readily understood.

In the form of the invention shown in 70 Figs. 1 and 2 the plate or disk is circular and is shown with its peripheral edge rigid with the band for the major portion of its circumference. This plate is indicated at 11 and its downwardly and inwardly in- 75 clinied leveling lip is shown at 12, the relation of which to the body of the plate or disk appears most clearly in Fig. 2.

In Fig. 2 the plate or disk 11^a is shown with one end portion bent inwardly and 80 downwardly, to form a leveling lip 12^a and in Fig. 4 the plate or disk 11^b has a leveling lip 12^b like the lip 12 of the form shown in Figs. 1 and 2.

In Fig. 5 I have shown a slightly modified 85 form wherein the downwardly and inwardly inclined lip or reverting flange 13 of the disk or plate 14 attached to the band 15, has a terminal extension 16 of relatively small proportions, which is bent upwardly 90 therefrom and attached to the lower surface of the disk or plate 14 so that according to this form the leveling lip is rigidly held and braced as distinguished from its more or less flexible nature in the structures pre- 95 viously described dependent of course upon the material of which the device is formed.

It is obvious that my device may be formed 100 of various materials, with the band and plate or disk either constructed separately and thereafter united, or with the disk and band stamped out of sheet material in the first instance and then pressed to form. In the latter instance it is obvious it will be necessary to slot the blank along an arcuate line 105 in order to free that portion of the plate from the band which is to be subsequently pressed inwardly and downwardly to form the leveling lip.

I am aware that devices of this general 110

nature have been before proposed in the form of rods or wires extending diametrically across the open end of a vessel, but I am also aware that such devices are faulty and ineffective owing to the fact that in drawing a heaping spoonful beneath the wire or rod the material is very likely to flow over the rod or wire and in this way prevent the desired result which cannot be prevented with my improved device in the exercise of ordinary care.

I claim:

- 15 1. A device of the character described consisting of a supporting band, a plate connected to and supported by said band and partially free therefrom, the free portion of said plate inclining inwardly and downwardly and forming a reverting lip for the purpose described.
- 20 2. A device of the character described consisting of a supporting band, a plate having a body portion whose edge joins the upper edge of the band, said plate also having a free portion forming a leveling lip inclined inwardly and downwardly beneath its said body.
- 25 3. A device of the character described in-

cluding means to engage the upper open end of a container for the purpose of forming a support, a plate whose edge is rigid with the said supporting means for the major portion thereof, and a lip carried by the plate and forming a reverting angle therewith as set forth.

4. A device of the character described including a disk having a flat body portion and a portion inclined at a reverting angle with respect to said body portion, and supporting means engageable with the open end of a container and with which the body portion of the disk is rigid.

5. A device of the character described consisting of a supporting band, a plate connected to and supported by said band and partially free therefrom, the free portion of said plate inclining inwardly and downwardly and forming a reverting lip, said lip having a terminal upstanding extension attached to the lower surface of the plate as described.

In testimony whereof I have affixed my signature.

HAROLD B. CRAIG.
